LETTER TRAY

Lute Wassmann, Chicago, Ill., assignor to Corry Jamestown Corporation, Corry, Pa., a corporation of New York

Filed Oct. 7, 1960, Ser. No. 62,425

Term of patent 7 years

(Cl. D74—9)

FIG. 1

FIG. 3

FIG. 1 is a perspective view of a letter tray showing my new design;

FIG. 2 is a side elevational view; and
FIG. 3 is a front end view thereof.

I claim:

The ornamental design for a letter tray, substantially as shown.
